FOLDING COT

Carl A. Dietrich, Carlisle, Iowa

Application March 31, 1941, Serial No. 386,022

4 Claims. (Cl. 5—110)

The object of my invention is to provide a folding cot of simple, durable and inexpensive construction and which, when in its upright position, may be moved to its folded position by simply moving the top of one of the cot end members toward the center of the cot, and when thus folded it will occupy a minimum of space for convenience in shipping and storage.

A further object is to provide means for automatically locking the cot in its upright position to thereby prevent accidental folding movement, which locking means may be quickly and easily released.

In the accompanying drawing—

Figure 1 shows a side view of the cot in its upright position;

Figure 2 shows a transverse sectional view of same on the line 2—2 of Figure 1;

Figure 3 shows a side view of the cot in folded position; and

Figure 4 shows a fragmentary plan view of one side of the cot in its upright position with parts of the cross-braces broken away to show engagement of the locking pin therein.

The cot comprises a mattress supporting frame having parallel side members 10 and a series of cross members 11. The ends of the side members are extended beyond the adjacent cross member, as shown at 12.

The head and foot members are alike, and each comprises two corner posts. Each post has an upright leg portion 13, and an upright head portion 14 which is offset longitudinally of the bed from the leg portion, the leg portions 13 being set inwardly toward the transverse center of the cot for purposes hereinafter made clear. Each cot post is pivotally connected with the mattress supporting frame by a screw 15.

Secured to the head portions 14 are cross pieces 16 forming a cot head member, the lower cross piece is so positioned that it will engage and rest upon the adjacent end 12 of the mattress supporting frame when the cot is in its upright position. This prevents the head member from moving outwardly away from the center of the cot beyond a vertical position.

For the purpose of firmly supporting the head and foot members in upright positions I have provided two supporting bars 17 and 18 for each side of the cot. The bar 17 is pivoted by means of a screw 19 to the head post member. Above the pivot point of the post member this bar is extended longitudinally and downwardly along the side of the mattress supporting member and is pivoted by a screw 20 to the leg member at the

5 other end of the cot below the pivoted point of the leg member. The other bar 18 is pivoted by a screw 21 to the leg member below the screw 19 and below the pivot of the post member, and is extended longitudinally of the cot and upwardly, and is pivoted by a screw 22 to the head of the post member at the opposite end of the cot above the pivot point of the post member.

These bars cross each other at the central part of the cot, and their ends are pivoted to the post members at points equally spaced apart from the pivots of the post members. Said bars are pivoted to the outer side portions of the post members, hence, they are at the outer sides of the mattress supporting member.

Washers 23 are placed on the pivot screws of the outer bars 17 to position them close to the outer surface of the inner bars.

For automatically locking the cot against accidental folding movement I have provided a flat spring 24 fixed to the central portion of one of the outer bars 17 and having a pin 25 at one end. An opening is formed in the inner bar 18 in such position that when the cot is in its upright position the pin will spring into the opening, and since no folding movement of the cot can occur unless the central portions of the bars 17 and 18 move longitudinally in opposite directions, the cot cannot be folded until the pin is moved out of the opening.

30 The cot is very simple and inexpensive, has few parts, and when in upright position is firmly braced in all directions and is strong and rigid. The end portions of the bars 17 and 18 above 35 the mattress supporting member serve as side boards for holding a mattress and bed clothes in position. To fold the cot it is only necessary to move the upper end of either the head member or the foot member toward the center of the cot. Movement is thereby transmitted through the crossed bars to the other member, and brings it to a completely folded position. By having the post members shaped as shown 40 in Figure 1, with the leg member 13 spaced inwardly from the head of the cot relative to the pivot screw 15, a weight upon the cot tends to move the lower end of the leg member toward the center of the cot, which movement is prevented by the engagement of the head member cross piece 16 engaging the projecting ends 12 of the mattress supporting member at points spaced beyond the pivot screw 15 at the side opposite from the pivot 12. Hence, weight on the cot has no tendency to fold the cot. When in 45 folded position the head and foot members lie

flat against the top of the mattress supporting member and the bars 17 and 18 are in line transversely of the cot with the mattress supporting member, and, as shown in Figure 3, the folded cot occupies a minimum of space for convenience in storage and shipping.

I claim as my invention:

1. A folding cot, comprising a mattress supporting member, a head member and a foot member, each comprising two post members pivoted to the sides of the mattress supporting member and having a cross bar positioned to rest upon a portion of said mattress supporting member at a point spaced outwardly beyond a vertical line through said pivot when the cot is upright, and each post having a leg member spaced inwardly toward the transverse center of the cot beyond a vertical line through said pivot, and crossed braces extended longitudinally of the mattress supporting member and spaced outwardly from the side edges thereof, each brace having one of its ends pivoted to one of the end members above the pivotal point of said end member on the mattress supporting member and having its other end pivoted to the other end member below its pivotal point.

2. A folding cot, comprising a mattress supporting member, a head member and a foot member, each comprising two post members pivoted to the sides of the mattress supporting member and having a cross bar positioned to rest upon a portion of said mattress supporting member at a point spaced outwardly beyond a vertical line through said pivot when the cot is upright, and each post having a leg member spaced inwardly toward the transverse center of the cot beyond a vertical line through said pivot, and crossed braces extended longitudinally of the mattress supporting member and spaced outwardly from the side edges thereof, each brace having one of its ends pivoted to one of the end members above the pivotal point of said end member on the mattress supporting member and having its other end pivoted to the other end member below its pivotal point, said crossed braces being so positioned relative to the head and foot members that when in their folded positions they will be in substantially the same horizontal plane as the mattress supporting member.

3. A folding cot, comprising a mattress supporting member, a head member and a foot member, each comprising two post members pivoted to the sides of the mattress supporting member and having a cross bar positioned to rest upon a portion of said mattress supporting member at a point spaced outwardly beyond a vertical line through said pivot when the cot is upright, and each post having a leg member spaced inwardly toward the transverse center of the cot beyond a vertical line through said pivot, and crossed braces extended longitudinally of the mattress supporting member and spaced outwardly from the side edges thereof, each brace having one of its ends pivoted to one of the end members above the pivotal point of said end member on the mattress supporting member and having its other end pivoted to the other end member below its pivotal point, and a releasable locking device at the crossed portions of said bars for holding them against horizontal movement relative to each other.

4. A folding cot, comprising a mattress supporting member, a head member and a foot member, each comprising two post members pivoted to the sides of the mattress supporting member and having a cross bar positioned to rest upon a portion of said mattress supporting member at a point spaced outwardly beyond a vertical line through said pivot when the cot is upright, and each post having a leg member spaced inwardly toward the transverse center of the cot beyond a vertical line through said pivot, and crossed braces extended longitudinally of the mattress supporting member and spaced outwardly from the side edges thereof, each brace having one of its ends pivoted to one of the end members above the pivotal point of said end member on the mattress supporting member and having its other end pivoted to the other end member below its pivotal point, each of said head and foot members having its legs offset inwardly toward the longitudinal center of the cot, and said mattress supporting member having a portion at each end extended longitudinally outward beyond its pivotal point, with the end member, and a portion of the end member being shaped to engage and rest upon said extended portion when in its open position.

CARL A. DIETRICH.
